PIPE AND CIGAR HOLDER ATTACHMENT

Jack L. Barbara, Port Jervis, N. Y.

Application August 29, 1949, Serial No. 112,885

2 Claims. (Cl. 131—228)

1

This invention relates to novel and useful improvements in attachment for pipe stems and cigar holder stems as well as cigarette holder stems and pieces.

An object of this invention is to lessen the possibility of nicotine laden moisture from entering directly into the mouth from the stem end.

Another object of this invention is to divide the smoke issuing from the stem into at least two independent streams, requiring the smoke to take a longer and more devious travel before entering into the mouth, thereby cooling the smoke.

Other objects and features will become apparent following the description of the illustrated form of the invention.

In the drawings:

Figure 1 is a perspective view of the attachment;

Figure 2 is a perspective view of the attachment, showing the same in another position;

Figure 3 is a sectional view of a part of a pipe stem and the attachment taken on the line 3—3 of Figure 4 and in the direction of the arrows, the actual stem being shown in elevation; and,

Figure 4 is a side view of the device showing its attachment to a typical pipe, cigarette or cigar holder stem.

The present invention consists of a pipe, cigar or cigarette holder stem attachment. A tubular member 10 is provided with a longitudinal slit 12 on one side thereof. There is an enlarged part of the slit 14 intermediate the ends of the slit and this enlarged part is adapted to be disposed over the central part of the stem 16 enlarged end portion 18.

Substantially at the point medially of the ends of the tubular member 10 there is a substantially V-shaped radially inwardly extending protuberance 20 when viewed from the inside of the tubular member. This substantially V-shaped raised portion is a divider and is adapted to engage the end surface of the stem 16.

In operation, the tubular member 10 is simply inserted on the enlarged end portion 18 of a stem of a smoking article. The raised portions 22 and 24 which are formed at the enlargement 14 in the slit 12 are disposed above and below the enlargement 18 of the stem 16. Hence, pockets are formed for accumulation of moisture from the stem which will accumulate in the pockets rather than flow directly through the tubular member.

The ends of the tubular member are open and form smoke passages for the smoke after it has been divided by the said divider 20.

Since the enlargement 14 in the slit is intermediate the ends of the tubular member, the material of the member on each side of the enlargement may be used as a friction clamp by engagement with the inside surfaces of the enlargement on the stem end.

Having described the invention, what is claimed as new is:

2

1. In combination with a smoker's article stem having an enlargement at one end thereof, a removable attachment for the end of the stem, said attachment comprising a tubular member or tube having a longitudinal slit in one wall thereof, with spaced edges of said tubular member defining said slit, raised portions intermediate the ends of said edges of the tubular member adapted to be disposed over the top and bottom of the enlargement on the stem, the material of the tube on each side of the tube raised portions being disposed over the inside edge of the stem enlargement, a smoke passage in each end portion of the tubular member, a transverse divider in said tubular member intermediate the ends thereof comprising an inwardly extending protuberance, diametrically opposite from said raised portions dividing said tube into said smoke passages to separate the smoke into two streams for flow 20 through the passages and the open ends of said tube, and said enlargement in said tube constituting moisture collection pockets.

2. For use with a smoker's article stem having an enlargement at one end thereof, an attachment for said end of said stem, said attachment comprising an open ended tubular member or tube having a longitudinal slit in the wall thereof, said tubular member having spaced edges defining said slit, said edges each having raised portions intermediate their ends and adapted to overlie a part of said stem adjacent the enlargement of said stem, the portions of the material of said tubular member adjacent and at said edges on each side of said raised portions constituting 35 a clamp to engage the enlargement of said stem, said tube having smoke passage means therein, a divider comprising a radially inwardly extending protuberance located transversely of said tube diametrically opposite from said raised portions 40 and separating said smoke passage means into individual smoke passages so that the smoke from the stem is diverted through each open end of said tube.
